UNITED STATES PATENT OFFICE.

THOMAS M. BRINTNALL, OF OAKLAND, CALIFORNIA, ASSIGNOR TO THE BRINTNALL MANUFACTURING COMPANY, A CORPORATION OF NEVADA.

LOWERING FLOOR.

Application filed October 11, 1924, Serial No. 743,930. Renewed May 14, 1927.

- The present invention relates to lowering floors, such as are employed in front of bank vaults, safes and the like, to meet conditions where the flooring immediately in front of a vault may be arranged on the same level as the floor interiorly of the vault, while capable of being temporarily lowered to allow for opening or closing of the vault door.
- 10 The principal object of this invention is to provide a floor of the character described which embodies simple, efficient and economical construction, present types being quite complicated and expensive.
- 15 Another object of the invention is to provide a floor of the character described, and an operating mechanism therefor, which may be readily installed or removed substantially as a unit.
- 20 Another object of the invention is to provide a floor of the character described, together with simple operating means therefor whereby the floor will always maintain a true level in either up or down position, as well as during its interval of motion.
- 25 Still another object of the invention is to provide an operating mechanism for floors of the above character which is simple and rugged in construction and in which the floor is maintained locked against accidental movement, both in up and down position.
- 30 A further object of the invention is to provide for locking the floor by inexpensive and dependable means.
- 35 Still other objects of my invention will appear hereinafter.
- I have illustrated by the accompanying drawings three embodiments of my invention.
- 40 In the said drawings:
- Figure 1 is a plan view of one embodiment of my invention, certain parts of the embodiment, as will be indicated hereinafter, being omitted for the sake of clearness;
- 45 Figure 2 is another plan view of the embodiment, on smaller scale, in which view all parts omitted in Figure 1 are shown, including a portion of a vault to which the embodiment is applied;
- 50 Figure 3 is a view in section on a line 3—3 of Figure 1 showing the mechanism and floor in the usual or raised position;
- 55 Figure 4 is a somewhat diagrammatic view of some of the parts shown in Figure
- 3, as they appear when the floor is in lowered position;
- Figure 5 is a view in cross section seen on a line 5—5 of Figure 1;
- 60 Figure 6 is a view in vertical section of a modified form showing the floor in raised position;
- Figure 7 is a similar view showing the floor in lowered position;
- Figure 8 is a plan view of the embodiment showing the parts underlying the floor, the latter being removed to reveal such underlying parts;
- 65 Figure 9 is a view in horizontal cross section of the parts shown in Figure 8; the floor being also shown in place.
- Figure 10 is a fragmentary plan view of another form of the invention, such form being adapted for operation by a person's weight.
- 70 Figure 11, is a view in vertical section thereof as the part appears in raised or normal position.
- Figure 12 is a similar view showing the parts when the floor is in lowered position.
- 75 Figure 13 is a fragmentary view in vertical section of a slight modification of the embodiment shown in Fig. 10.
- Referring now to Figures 1 to 5, inclusive, particularly, 15 indicates the front wall of a vault provided with a door jamb 16 (see Figures 2 and 5; also Figure 9). The door jamb is stepped as usual in conformance with the construction of usual vault doors, such as 17. The floor, or floor level, 80 interiorly of the vault is above the level of the lowermost part of the vault door, as in the case illustrated in Figure 9.
- To provide for a flooring externally of the vault, level with the floor of the vault, a movable floor or platform 20 is provided. A pit 21 is provided under said movable floor. It will be apparent, from Figures 2, 5 and 9, that the door can be swung from open to closed position, or vice versa, only 85 when the floor is lowered. That end of the floor which is adjacent the door when the latter is in open position, as shown in Figure 2, is narrower than the other end. The reduced part of said floor is complemented 90 by a fixed shield or floor member 23, which is fixedly disposed under the open door at the level which the movable floor assumes when in lowered position. Said member 23 covers that portion of the pit coming below 95

the open door and provides against accidents by covering an unsightly and possibly dangerous exposed part of the pit.

From the lowering floor to the vault floor 5 a light portable bridge 24 is usually extended to provide a level walk.

The pit is provided with a rectangular frame made up of angle irons or the like 25, 26, 27 and 28, respectively. Vertical angle 10 irons or the like 29 and 30, together with channels 31 and 32, provide legs, as well as interconnecting means for the frame members. A pair of spaced end walls, such as 33, and spaced side walls, such as 34, provide 15 a complete metal lining for the upper part of the pit, said lining being hereinafter termed the pit casing. The pit casing is greater in width than the rectangular frame of angle irons. In Figure 1, the lowering 20 floor or platform is shown removed, as well as all that portion of the pit casing which comes above the said frame. As shown particularly in Figure 3, the pit casing is also supported by the legs 29, 30, 31 and 32, and 25 is thereby incorporated in a unit with the frame. Therefore, the complete unit of the pit casing and the frame and leg members may be installed or removed from a pit as a unit. In designing a lowering floor for a 30 new bank, the complete device may be built and assembled outside of and even remotely from the pit, and later be quickly installed.

In conformance with a salient feature of the invention, the upper edges 36 of the 35 longitudinal frame members 25 and 27 are disposed on a true horizontal plane, preferably, and provide tracks on which flanged wheels such as 37 may ride. Said wheels are carried by trucks 38 which include truck-frame members 39 spaced apart and tied by members 40. Each truck, preferably, has four wheels and respective trucks, two in number preferably, are disposed at respective ends of the pit. Frame members 25 and 40 28 are joined by a plate 41 in which is revolvably mounted a centrally located pinion gear 42, an arched plate 43 providing an upper bearing and guard for the pinion and its shaft 44. Each truck is provided with a 45 rack 45, tied to its truck as at 45' and extending out to operatively engage the pinion.

It will be apparent now that when one truck is moved toward the center of the pit the other truck, through the medium of the pinion and the other rack, will also move toward the center. One truck is provided with a spring 50 and the other truck is moved in either direction by means of a lever 51, and a link 52. The link is pivoted to the 55 truck, as at 53, and the lever is pivoted at a fixed point, such as 54, and connects pivotally with the link at 55.

At one end of the pit casing, at a suitable 60 location, a box-like casing 56 is provided, enclosing a small space 57. A transverse shaft

58 is supported by opposite sides of the casing and on this shaft a lever 59 is mounted to be oscillated forwardly or rearwardly with regard to the direction of travel of the trucks. The lever terminates in a socketed 70 end 60 in which may be inserted a removable portable lever handle 61. The lever 59 is connected with the first mentioned lever by means of a long link 62 and pivot pins 63 and 64, respectively. Therefore, when the handle is moved toward the pit the trucks will move apart and when the handle is oppositely moved the trucks will move toward each other.

For each truck there is provided a shaft or 80 axle 66 having flanged wheels 67 which are revoluble independently of the truck wheels and which serve another and distinct purpose, as will now appear. In fact, when the trucks move in either direction the attached 85 shaft 66 moves therewith, carrying its wheels. In fact, the truck moving mechanism is provided for the purpose of controlling and changing the location of said wheels within 90 the pit.

The floor or platform is of simple construction and includes a single plate 67 reinforced below by angle irons 68. The plate may be ornamentally or otherwise covered by tile 69 or other suitable flooring, such as 95 is employed by those skilled in the art. A salient feature of the floor is that it includes 100 vertically depending members 70', one for each of the wheels 67. The normal position of the four wheels 67 with regard to the floor and vault is best understood by referring to Figure 2 particularly, in which said wheels and their shafts 66 are carefully shown in broken lines. Each of the depending members is provided with a lower inclined edge 105 or plane 68' which is adapted to ride on the perimeter of a corresponding wheel. In the preferred construction, as shown, the inclined plane members are arranged in pairs, 110 one pair adjacent each end of the floor. The members of a pair are arranged in parallel relation with their planes similarly arranged, while one pair of members is opposed to the other pair of members, so that the inclined surfaces of one pair of members are inclined 115 oppositely to the surfaces of the other pair.

To best explain the operation of the device, it will be assumed that the trucks are stationary in the position shown in Figure 3. The floor may be caused to repose directly 120 on the four wheels. The floor will remain level and is evenly supported at four properly arranged points. It will be noted that the inclines start from a lower horizontal surface 70 and also terminate at an upper horizontal surface 71. Ordinarily the trucks are moved far enough apart to provide for the lower surface reposing on the rims of the wheels. Therefore, the weight of the 125 floor cannot exert any force to tend to move 130

the trucks toward each other. The same condition applies when the trucks are moved toward each other far enough to permit surfaces 71 to rest on the wheels. It will be seen that simple and positive means are, therefore, provided for holding the floor positively in upper or lower positions, regardless of any sudden weight which may be imposed thereon. To lower the floor the handle is moved to force the trucks toward each other. First toward movement of the trucks brings the wheels under the inclines. Owing to the slight or comparatively ineffective angle of the incline, the weight of the platform is applied quite indirectly in forcing the trucks together and friction will act to some extent to prevent undesirably fast lowering or dropping of the floor. The slight angle of inclination, when the floor is being raised, works quite oppositely to actually reduce friction. In fact, the angles and leverages are such that the floor may be raised with comparative ease by any person of ordinary strength. When the floor is lowered to lowermost position, it is level with the shield which underlies the open door. When the floor is in such position the vault door may be swung to closed position.

In the form of the invention shown in Figures 6, 7, 8 and 9, a floor 79 is provided with a somewhat different form of inclined plane member, designated by the numeral 80. Said members are each provided with an inclined surface 81, as well as a reserve inclined surface 82. The latter is not used ordinarily, but provides for the member being reversible, to increase its life, and make all such members identical and interchangeable. Several such members depend from the lowering floor while other such members 80' are extended upwardly from the floor 83 of the pit. The pit is lined with a pit casing or lining 84 and the floor 79 is provided with guide rollers running against the pit casing to insure against horizontal movement of the floor, and to take up any lateral thrust. A single large truck 85 is provided which is made up of frame members 86, 87, 88 and 89. A plurality of transverse shafts 90 are revolvably mounted in and carried by said truck. Forward movement of the truck is limited by abutment of projections 91 with the pit casing. A small box-like casing 92 houses a shaft 93 on which rocks an operating lever 94. The latter is pivotally connected, as at 95, to a link 96 which is pivotally connected at 97 to a yoke 98. Yoke 98 is bolted to the truck frame, as at 99. The truck is advanced and retracted in the pit by movement of the lever 94. Wheels 100 are provided, two for each shaft, and said wheels are shown as keyed to their respective shafts as at 101.

Other wheels 102 are provided, said wheels being loose running fits on the shafts, so that they may revolve independently of keyed wheels and the shafts. Wheels 102 are the running wheels for the truck and these incline members which are arranged on the floor of the pit serve as trucks for said 70 wheels.

The incline members which are carried by the lowering floor ride on the keyed wheels. The incline plane members are provided each with resting surfaces 103 and 104, respectively, to provide for holding the floor securely in raised as well as lowered position. As the trucks and attached wheels are moved rearwardly, the truck not only will descend toward the floor of the pit, but the movable floor will also descend relative to the truck. Therefore, the descent of the moving floor is twice as fast as it would be if the tracks were level, instead of inclined. Figure 6 clearly shows the relative positions of parts when the floor is in uppermost position. Figure 7 shows the position of the same parts when the floor is lowered, the floor in each case actually resting on a flat surface rather than on an inclined plane. 90 One of the wheels on which the floor rides is shown in Figure 8 as moved inward from the other wheel. Said inwardly positioned wheel is to provide for a narrow portion (not shown) at that end of the floor. The angles of the inclined surfaces are designed to reduce friction when the floor is being raised, while increasing friction during lowering to prevent too sudden drop on the part of the floor. The operation of the embodiment just described is practically the same as the first described, but the last described embodiment provides for maximum lift in a pit of minimum depth.

In the form of the invention shown in Figs. 10, 11 and 12, a floor 110 is provided having inclined surface members 111, a single horizontally movable frame 112 is provided which comprises end members 114 and side members 113. The side members carry inwardly projecting stub axles 115, on which wheels 116 are mounted. Each two adjacent stub axles are connected to each other by a beam 117. In Fig. 10, only one side of the complete embodiment is shown, but it is understood that the other side is identical. From a beam, such as 117, on one side, a fixed axle 118 extends laterally across the frame to a similar opposed beam, which as explained, is not shown. Also the drawing shows, in complete detail only one typical end of the embodiment, and it is to be understood that the end not shown is identical to the end shown. The complete frame should have four sets of wheels, such as 116.

The wheels, and therefore the complete frame, ride on tracks 119 which are situate in the bottom of the pit 120. The frame may be termed a truck; the long fixed axles 130

carrying wheels or rollers 121 on which the incline surface members ride. All inclines should face in one direction so that when the frame is moved in one direction the floor 5 will be raised, or the floor will be lowered when the frame is moved in the other direction. Each of the incline members include the flat resting surfaces 122 and 123.

In a casing 124, attached to the pit casing 10 125, I provide an elevating platform 126 having a plurality of legs 127, provided with casters 128 which ride on vertical track members 129 and insure straight vertical movement on the part of the platform. The 15 elevating platform is connected with the truck or frame by links 130 and 133, and a bell crank 132. The bell crank is pivoted on a shaft 131, which is held in place by two spaced plates 134, attached to the small casing 124, as at 135. A bearing member 136 and a pin 137 connect the platform with the link 130. A pivot pin 138 connects the link 130 with the bell crank, while pivot pins 139 and 140 provide for the link 131 being connected with the truck.

It will be apparent now that as the floor descends, the truck will move to the right and the platform will be elevated. When the platform is in elevated position the upper flat surfaces of the incline members securely hold the floor in down position. When suitable weight is imposed on the platform it will be depressed and the truck will be forcibly moved to the left to cause 30 the floor to rise. When the floor is raised its wheels will rest on the lower flat surface of the incline members.

When in raised position the floor will support any weight whatever that may be imposed upon it without being depressed. If, 40 and when, it is desired to lower the floor the truck must be moved to the right a slight distance so that the supporting wheels or rollers will be in contact with inclined surfaces. For the purpose of moving the floor slightly to the right so that it may subsequently descend by its own weight, I provide a push rod 140, a bell crank 141, and a connecting link 142. Said link has pivot 45 pins 143 and 144, respectively, connecting it with the bell crank. The latter is supported by a pin 145, and spaced webs 146. The lower end 147 of the bell crank abuts the extension 148 of the truck, so that upon the push rod being depressed the truck is forced to the right.

It will now be apparent that to lower the floor shown in Figs. 10, 11, and 12 it is only necessary to push the push rod. To raise 60 the floor again from the position shown in Fig. 12, the operator places one foot, or his entire weight, on the elevated platform, and by means of the leverage provided, an extremely heavy floor is easily raised.

In the form of the invention shown in

Fig. 13, the wheel is fixed to the floor, as at 150, while the incline member is attached, as at 151 to the truck. Such transposition of incline members and wheels may be applied to any of the embodiments described.

While I have shown and described specific constructions and arrangements of parts, I do not limit myself thereto and may alter the constructions and arrangements as I desire, without enlarging the scope of my invention, within the appended claims.

I claim as my invention:

1. In combination, a pit, a platform movable vertically in said pit, said platform so fitting therein as to be practically precluded from horizontal movement, inclined plane members and wheels, one of the last mentioned being movable horizontally and the other of the last mentioned being fixed to the platform, a lever operable externally of the pit, and connections between said lever and said horizontally movable members.

2. In combination, a pit, a platform movable vertically in said pit, said platform so fitting therein as to be practically precluded from horizontal movement, inclined plane members and wheels, one of the last mentioned being movable horizontally and the other of the last mentioned being fixed to the platform, a lever operable externally of the pit, and connections between said lever and said horizontally movable members; said floor being supported entirely by said wheels and inclined plane members.

3. In combination, a pit, a platform movable vertically in said pit; said platform so fitting therein as to be practically precluded from horizontal movement, inclined plane members and wheels, one of the last mentioned being fixed to the platform, a lever operable externally of the pit, and connections between said lever and said horizontally movable members; the inclined plane members being provided with a horizontal continuation of the plane surface, said wheels, inclined plane members and platform so relatively positioned that the wheels and said horizontal continuations are in contact when the floor is in fully raised position.

4. In combination, a pit, a platform movable vertically in said pit, said platform so fitting therein as to be practically precluded from horizontal movement, inclined plane members and wheels, one of the last mentioned being movable horizontally and the other end of the last mentioned being fixed to the platform, a lever operable externally of the pit, and connections between said lever and said horizontally movable members; said platform being supported entirely by wheels and inclined plane members, said inclined plane members being provided with a horizontal continuation of the plane surface, said wheels, inclined plane members and platform relatively positioned that the

wheels and said horizontal continuations are in contact when the floor is in fully raised position.

5. In combination, a vault, a floor to said vault, a door to said vault having a lower portion below the level of the vault floor, a pit in front of said vault and door, a floating floor in said pit movable upward to the level of the vault floor and movable downward to below the lowermost portion of said door, inclined plane members, wheels co-acting therewith, means for moving said wheels in a general horizontal direction relative to said inclined plane members, and a floating floor supported by said wheels and inclined plane members.

6. In combination, a vault, a floor to said vault, a door to said vault having a lower portion below the level of the vault floor, a pit in front of said vault and door, a floating floor in said pit movable upward to the level of the vault floor and movable downward to below the lowermost portion of said door, inclined plane members, wheels co-acting therewith, means for moving said wheels in a general horizontal direction relative to said inclined plane members, a floating floor supported by said wheels and inclined plane members, and means for preventing horizontal travel on the part of said floating floor.

7. In combination, a vault, a floor to said vault, a door to said vault having a lower portion below the level of the vault floor, a pit in front of said vault and door, a floating floor in said pit movable upward to the level of the vault floor and movable downward to below the lowermost portion of said door, inclined plane members, wheels co-acting therewith, means for moving said wheels in a general horizontal direction relative to said inclined plane members, and a floating floor supported by said wheels and inclined plane members, said wheel moving means operable from above the floating floor.

8. In combination, a vault, a floor to said vault, a door to said vault having a lower portion below the level of the vault floor, a pit in front of said vault and door, a floating floor in said pit movable upward to the level of the vault and movable downward to below the lowermost portion of said door, inclined plane members, wheels co-acting therewith, means for moving said wheels in a general horizontal direction relative to said inclined plane members, a floating floor supported by said wheels and inclined plane members, and means for preventing horizontal travel on the part of said floating floor, said wheel moving means operable from above the floor.

9. In combination, a pit, generally horizontal tracks in said pit, trucks running on said tracks, a floating floor movable vertically in said pit, and presenting inclined sur-

faces at its under side, and means carried by said trucks co-acting with said inclined surfaces whereby horizontal movement of the trucks will provide vertical movement on the part of said floor.

10. In combination, a pit, generally horizontal tracks in said pit, trucks running on said tracks, a floating floor movable vertically in said pit, and presenting inclined surfaces at its under side and means carried by said trucks co-acting with said inclined surfaces whereby horizontal movement of the trucks will provide vertical movement on the part of said floor, said floor resting solely and detachably upon the means carried by said trucks.

11. In combination, a pit generally horizontal tracks in said pit, trucks running on said tracks, a floating floor movable vertically in said pit, and presenting inclined surfaces at its under side, and means carried by said trucks co-acting with said inclined surfaces whereby horizontal movement of the trucks will provide vertical movement on the part of said floor, said floor resting solely and detachably upon the means carried by said trucks, and means to prevent other than vertical movement on the part of said floor.

12. In a device of the class described, inclined plane members presenting a lower horizontal surface, an upper horizontal surface, and inclined surfaces connecting each lower horizontal surface with the corresponding upper horizontal surface, friction reducing means below said members adapted to support said members, means for moving said friction reducing means in a general horizontal direction to produce raising or lowering of said members, and a floating floor arranged to be raised directly by and with said inclined plane members.

13. In a device of the class described, generally horizontal tracks, trucks running on said tracks, roller means carried by said trucks, a floor above said trucks presenting inclined surfaces to said roller means, and a pit casing in which said floor is vertically movable and guided; said floor being full floating and supported entirely by said roller means.

14. In a device of the class described, generally horizontal tracks, trucks running on said tracks, roller means carried by said trucks, a floor above said trucks presenting inclined surfaces to said roller means, means operable from above said floor for causing said trucks to travel along said tracks, and a pit casing in which said floor is vertically movable and guided; said floor being full floating and supported entirely by said roller means.

15. In a device of the class described, a parallel arrangement of frame members, two parallel members of said frame presenting upper edges, a wheeled truck adapted to

run with its wheels riding on said upper edges, roller means carried by said trucks, a pit casing including walls arranged in conformance with the arrangement of said frame members, means tying said frame members and said pit casing walls in a unit, a floating floor vertically movable in said pit and prevented from horizontal travel by the walls of said pit casing, inclined surface members depending from said floor and presenting inclined surfaces to said roller means, whereby travel of said wheeled trucks in a general horizontal direction will act to raise or lower said floor.

16. In a device of the class described, a parallelogram arrangement of frame members, two parallel members of said frame presenting upper edges, a wheeled truck adapted to run with its wheels riding on said upper edges, roller means carried by said trucks, a pit casing including walls arranged in conformance with the arrangement of said frame members, means tying said frame members and said pit casing walls in a unit, a floating floor vertically movable in said pit and prevented from horizontal travel by the walls of said pit casing, inclined surface members depending from said floor and presenting inclined surfaces to said roller means, whereby travel of said wheeled trucks in a general horizontal direction will act to raise or lower said floor.

rection will act to raise or lower said floor, and means operable from above said floor for imparting a general horizontal travel to said trucks.

17. In combination, walls encompassing an open pit, two members in said pit movable in a general horizontal direction, toward and away from each other, roller means carried by said horizontally movable members, and a floor freely floating in said pit, said floor presenting oppositely inclined surfaces to corresponding roller members whereby forward or retrograde movement of said members will act to raise or lower said floor.

18. In combination, walls encompassing an open pit, two members in said pit movable in a general horizontal direction, toward and away from each other, roller means carried by said horizontally movable members, a floor freely floating in said pit, said floor presenting oppositely inclined surfaces to corresponding roller members whereby forward or retrograde movement of said members will act to raise or lower said floor, and means operable by a person standing on or near said floor for imparting forward and retrograde movement on the part of said two members.

THOMAS M. BRINTNALL.
